ATTORNEY

UNITED STATES PATENT OFFICE.

AYRES P. MERRILL, OF NATCHEZ, MISSISSIPPI.

GATE.

Application filed September 4, 1925. Serial No. 54,554.

This invention relates to rotary gates and its principal object is to provide a gravity actuated gate which after being arranged in an open position will return by gravity to a position to extend across the gate opening.

A further object of the invention is to provide a gate embodying a vertical post provided with a track or runway which may be solid or made up of sections and which has raised parts and depressions therebetween, together with a rotatable gate equipped with elements, such as rollers, balls or the like which are movable over the cam track or runway and which after passing over the raised parts of the track travels into the depressed parts thereof to return the gate to a position to extend across the roadway.

With the preceding and other objects and advantages in view, the invention consists in the novel combination of elements, construction, arrangement of parts and operations, to be hereinafter specifically referred to, claimed and illustrated in the accompanying drawings, wherein:

25 Figure 1 is an elevation of the gate in closed position.

Figure 2 is a similar view showing parts in section.

Figure 3 is a top plan view of the gate, 30 the dotted line position indicating the gate in open position.

Figure 4 is an end elevation of the gate.

Figure 5 is a sectional view taken on the line 5—5 of Figure 3.

35 Figure 6 is a similar view taken at right angles to Figure 5.

Referring to the drawings in detail where-in corresponding characters of reference denote corresponding parts throughout the 40 several views, the numeral 5 designates a vertically arranged post and rotatable about this post adjacent its ends are rings 6. These rings are formed at diametrically opposite points, with channel-shaped brackets 7. The 45 numeral 10 designates a pair of gate sections which are arranged upon opposite sides of the post 5 and which have their ends received in the brackets 7 and secured thereto by means 11. A collar 12 is also rotatable about the post. The collar 12 is provided at diametrically opposite points with pairs of spaced ears 13 which are secured to the gates, as at 14.

50 Annular tracks or runways 15 are fixed, 55 by means 16, on the post directly below the

rings 6. The upper face of each of these tracks 15 is concaved or dished from diametrically opposite points and afford triangular shaped projections 17 that are disposed at diametrically opposite points and 60 concaved depressions 17' between said projections. Carried by each of the rings 16 and journaled inwardly therefrom at diametrically opposite points, are rollers 18 which rest on and are movable over the cam 65 track or runway and projections 17.

Secured to the lower portions and upon the opposite sides of the respective gates 10 there are bars 19 whose inner ends are secured directly to the gate, as at 20, while 70 their opposite ends are fixed on brace elements 21 that are secured to the ends of the gates. By this arrangement each bar 19 extends at an angle from the gate on which it is fixed, as shown in Figure 3. As many 75 bars 19 as desired may be secured in the same manner as shown, without departing from the spirit of the invention.

As shown in dotted lines in Figure 3 the bars 19 are in the nature of contact elements 80 and are adapted to be engaged by the front wheels of an approaching vehicle to rotate the gates to open position as is also shown by the dotted lines in the said figure. The bars may also be of a height to be engaged 85 by a bumper of an automobile.

As the gate is rotated to open position by impact from the automobile or by hand, the rollers 18 traveling over the projections 17 of the track or runway will raise the gate 90 and after the gate has moved off of the said projections they will travel into the depressions 17' and cause the gate to return to initial closed position.

While I have shown and described the preferred embodiment of my invention, I desire to have it understood that such changes may be made in the form, construction, arrangement of parts and operations, as will not depart from the spirit of the invention 95 or the scope of the subjoined claims.

What is claimed is:

A gate construction including a cross sectionally rounded post, upper and lower annular members secured on the post, each of 105 said members having their upper faces concaved and dished from diametrically opposite points to provide tracks and to afford, at its said diametrically opposite points projections, and concaved walls between said 110

projections, a gate comprising two sections, ring members having oppositely directed bifurcated arms which receive therein and have fixed thereto the respective gate sections, said ring members being disposed opposite the tracks and having journaled therein rollers which rest on the tracks, and a collar surrounding the post and having oppositely extending pairs of ears which receive therein and are fixed to the gate ¹⁰ sections.

In testimony whereof I affix my signature.

AYRES P. MERRILL.
